UNITED STATES PATENT OFFICE.

EPPA H. RYON, OF WALTHAM, MASSACHUSETTS, ASSIGNOR TO CROMPTON & KNOWLES
LOOM WORKS, A CORPORATION OF MASSACHUSETTS.

LOOM.

1,069,034.

Specification of Letters Patent.

Patented July 29, 1913.

Application filed November 27, 1911. Serial No. 662,538.

To all whom it may concern:

Be it known that I, EPPA H. RYON, a citizen of the United States, residing at Waltham, in the county of Middlesex and State 5 of Massachusetts, have invented certain new and useful Improvements in Looms, of which the following is a specification.

My invention relates to looms, and particularly to the head motion of a loom of the 10 well known Knowles type, so-termed, shown and described in Re-issue Letters Patent, No. 7,784, in which vibrator gears are moved according to the selection of the pattern indicating mechanism, and brought 15 into mesh with the upper cylinder gear, or the lower cylinder gear, and rotated thereby, in one or the other direction, to operate the harnesses, or the drop boxes, in the usual way.

20 The object of my invention is to substitute for the ordinary iron roller chain, a peg pattern chain, and provide mechanism which, through the indications of the pattern chain, causes the vibrator gears to be 25 raised or lowered, and brought into mesh with the upper cylinder gear, or the lower cylinder gear, and rotated thereby in one or the other direction, to operate the harnesses, or the drop boxes.

30 My invention consists in certain novel features of construction of my improvements, as will be hereinafter fully described.

I have only shown in the drawings a detached portion of the head motion of the 35 Knowles type, above referred to, with my improvements combined therewith, sufficient to enable those skilled in the art to understand the construction and operation 40 thereof.

Referring to the drawings:—Figure 1 is a front elevation of a Knowles head motion with my improvements applied thereto. Fig. 2 shows the head motion shown in Fig. 45 1, partially in section; some of the parts shown in Fig. 1 are left off to more clearly illustrate the operating mechanism of my improvements. Fig. 3 corresponds to Fig. 2, but shows some of the parts in another 50 position, and, Fig. 4 is a detached plan view of the pattern indicating levers, and some of the parts shown in Fig. 3, looking in the direction of arrow *a*, same figure.

55 In the accompanying drawings, 1 is a portion of the loom arch, which has mounted

thereon the stand or end frame 2, which supports the several parts of the head motion. The head motion shown in the drawings, is the well known Knowles type above referred to, and comprises the upper cylinder gear 60 3, fast on the cylinder gear shaft 4, and the lower cylinder gear 5, fast on the lower cylinder gear shaft 6. The vibrator lever 7, which is pivoted at one end on a stationary rod 8, carries the vibrator gear 9, which 65 meshes with the upper cylinder gear 3, or the lower cylinder gear 5, by being raised or lowered by the pattern mechanism, to be hereinafter described, to communicate a reciprocating movement to the harness levers, 70 or to the shuttle box motion levers, not shown, through the vibrator connector 10. A pinion 11 on the cylinder gear shaft 6, meshes with and drives a gear 12 loose on the shaft 13. All of the above mentioned 75 parts may be of the usual and well known construction.

I will now describe my improvements. On the end of the shaft 4 of the upper cylinder gear 3 is in this instance secured a cam 80 14, which engages a roll 15, mounted on a stud 16 on a cam slide 17. A rod 18 is adjustably connected at one end to the slide 17, and at its other end is pivotally connected to a stud 19 on the end of one arm of 85 a lever 20, which has its hub 20' mounted on a transverse shaft 21. A helically coiled contraction spring 22 is attached at one end to the arm 20, and at its other end to a stud 23 on the frame 2, and acts to yieldingly 90 hold the roll 15 in engagement with the cam 14. Through the revolution of the cylinder gear 3 and the shaft 4, the cam 14 causes a rocking motion to be communicated to the shaft 21. The shaft 21 has secured thereon, 95 preferably at each end thereof, a downwardly extending arm 24, which arms carry, at their lower ends, the knife bar 25, see Figs. 2 and 3. The knife bar 25 is adapted to engage the free notched ends 26' of 100 the connector fingers 26, when said fingers are in their lowered position, as shown in Fig. 3. The other end of the fingers 26 are each pivotally connected to an arm 27, which has its open end, or yoke shaped hub 27' 105 loosely mounted on the shaft 13, and in this instance held thereon to prevent it from accidental removal by a split or cotter pin 27''. A stud 28, on each arm 27, carries a roll 29, which is adapted to engage the lower 110

edge of the run 7' on the vibrator lever 7, and causes said vibrator lever to be raised, when the arm 27 is moved to the right, as shown in Fig. 3. The connector fingers 26 are raised and lowered through the indications of a pattern chain 30, comprising bars linked together, and carrying pegs 31. The chain 30 is carried on a cylinder 32, mounted on a shaft 33. The end of the shaft 33 has mounted thereon the gear 34, see Fig. 10, which meshes with and is driven by a gear 35, loose on the shaft 13, and fast to the gear 12.

15 A series of indicator levers 36 extend over the pattern chain 30, and are pivotally mounted on a transverse rod 37 at one end, which end has an upwardly extending arm 36' thereon, which carries an adjusting screw 38, which is adapted to travel on the 20 lower edge of the connector finger 26, and form an adjustable engaging surface between the indicator lever 36 and the connector finger 26. The extreme end 36'' on the arm 36' extends above the lower edge 25 of the connector finger 26, and a rib or flange 26'', on one side of the connector finger 26, acts as a guide or bearing surface between said fingers, see Fig. 4. By means of the adjusting screw 38 any wear of the 30 parts is provided for, and an adjustment may be obtained so that the levers 36 will always be properly aligned for the bar 25. The free ends of the indicator levers 36 extend between pins 39' on a comb bar 39; 35 said bar limits the downward motion of said indicator levers at their free end.

To raise the indicator levers 36, to allow a peg 31 on the chain 30 to pass under said levers, I in this instance provide a transverse bar 40, which extends under the levers 36 40 at their free ends. The bar 40 is attached at each end to the lower end of an upright bar 41, which is pivotally attached at its upper end to an arm on the lever 20. A link 42, 45 see Fig. 1, is pivotally attached at one end to the upright bar 41, and at its other end to the frame part of the head motion, and acts to hold the transverse bar 40 in proper position relative to the levers 36. A transverse rod 43 limits the rocking motion of the 50 arms 27, see Figs. 2 and 3.

In the rotation of the pattern chain 30, when a peg 31 thereon comes under an indicator lever 36, see Fig. 3, the lever 36 55 is raised at its free end, and the opposite end of said lever, which carries the screw 38 is moved to the right, and the notched end 26' of the connector finger 26 is allowed to drop down and engage the knife bar 25. 60 The movement of the knife bar 25 to the right in Fig. 3, through the rotation of the cam 14, and intermediate connections, will move the arm 27 and carry the roll 29 under the run 7' on the vibrator lever 7, to 65 raise the vibrator gear 9 into mesh with

the upper cylinder gear 3, as shown in Fig. 3.

In the rotation of the pattern chain 30, when a peg 31 passes from under the pattern indicator lever 36, and a blank comes 70 under said lever, see Fig. 2, the free end of the lever 36 will drop down and cause the end 36'', carrying the screw 38, to be moved to the left, and the engagement of the extended end 36'', with the rib 26'' in the finger 26, will move said finger to the left, and draw the roll 29 from under the run 7' on the vibrator lever 7, to disengage it from said run 7', and allow the vibrator lever 7 to drop into engagement with the lower cylinder gear 5, as shown in Fig. 2. The travel 75 of the lower edge of the finger 26 on the screw 38, will raise said finger out of the path of the vibrating knife bar 25, as shown in Fig. 2.

80 It will be understood that the details of construction of my improvements may be varied if desired.

Having thus described my invention, what I claim as new and desire to secure by Letters Patent is:—

1. In harness mechanism for looms, an upper cylinder gear, a lower cylinder gear, a vibrator gear, a vibrator lever having a run thereon, a pivotally mounted lever having a roll or surface thereon to coöperate with said run, a pivotally mounted pattern chain indicator finger, a pattern surface to coöperate therewith, mechanism coöperating with said pivotally mounted lever to move 95 the same on its pivotal support to positively raise said vibrator lever, connections intermediate said pivotally mounted lever and said pattern chain indicator finger, whereby the engaging surface on said pivotally mounted lever is positively withdrawn from the run on said vibrator lever, through the lowering of the pattern chain indicator finger during the revolution of the pattern surface.

110 2. In harness mechanism for looms, an upper cylinder gear, a lower cylinder gear, a vibrator gear, a vibrator lever having a run thereon, a pivotally mounted lever having a roll or surface thereon to coöperate 115 with said run, a connector finger pivotally attached to said pivotally mounted lever, a reciprocating knife bar to engage said connector finger, to positively move the roll or surface on said pivotally mounted lever under said run, means for communicating a reciprocating movement to said knife bar, a pivotally mounted pattern chain indicator finger, a pattern surface to coöperate therewith, connections intermediate said indicator finger and said connector finger, whereby on the withdrawal of a pattern indicator from under the pattern indicator finger, said connector finger will be moved to positively withdraw the roll or surface on said 120 125 130 135 140 145 150 155 160 165 170 175 180 185 190 195 200 205 210 215 220 225 230 235 240 245 250 255 260 265 270 275 280 285 pivottally mounted lever from engagement with the run on said vibrator lever.

3. In harness mechanism for looms, an upper cylinder gear, a lower cylinder gear, 5 a vibrator gear, a vibrator lever having a run thereon, a pivottally mounted lever having a roll or surface thereon to coöperate with said run, a connector finger, pivottally attached to said pivottally mounted lever, a reciprocating knife bar to engage said connector finger to positively move the roll or surface on said pivottally mounted lever under said run, means for communicating a reciprocating movement to said knife bar, 10 said means comprising a cam on a cylinder gear shaft, and connections, intermediate said cam and said reciprocating bar, a pivottally mounted pattern chain indicator finger, a pattern surface to coöperate therewith, 15 connections intermediate said indicator finger and said connector finger, whereby on the withdrawal of a pattern indicator from under the pattern indicator finger, said connector finger will be moved to positively operate 20 said cam and said reciprocating bar, a pivottally mounted pattern chain indicator finger, a pattern surface to coöperate therewith, 25 connections intermediate said indicator finger and said connector finger, whereby on the withdrawal of a pattern indicator from under the pattern indicator finger, said connector finger will be moved to positively operate 30 withdraw the roll or surface on said pivottally mounted lever from engagement with the run on said vibrator lever.

4. In a harness mechanism of the class described, an upper cylinder gear, a lower cylinder gear, a vibrator gear, a vibrator lever having a run thereon, a pivottally mounted lever having a roll or surface thereon to coöperate with said run, a connector

finger pivottally attached to said pivottally mounted lever, a reciprocating knife bar to engage said connector finger, to positively move the roll or surface on said pivottally mounted lever under said run, means for communicating a reciprocating movement to said knife bar, a pivottally mounted pattern chain indicator finger, a pattern surface to coöperate therewith, connections intermediate said indicator finger and said connector finger, whereby on the withdrawal of a pattern indicator from under the pattern indicator finger, said connector finger will be moved to positively withdraw the roll or surface on said pivottally mounted lever from engagement with the run on said vibrator lever, and means for positively 45 raising the pivottally mounted pattern chain indicator fingers at their free ends, for the passage of a pattern indicator on the pattern chain under said fingers.

5. In a harness mechanism for looms, a connector finger, means to positively operate said connector finger, a pattern indicator lever, pattern surfaces to operate said pattern indicator lever, and an adjustable engaging surface comprising an adjusting screw between said connector finger and said pattern indicator lever.

EPPA H. RYON.
